UNITED STATES PATENT OFFICE.

JAMES R. HASKELL, OF PASSAIC, NEW JERSEY, ASSIGNOR TO ARTHUR B. JOHNSON, TRUSTEE, OF UTICA, NEW YORK.

WAD FOR ORDNANCE.

SPECIFICATION forming part of Letters Patent No. 241,979, dated May 24, 1881.

Application filed October 28, 1880. (No model.)

To all whom it may concern:

Be it known that I, JAMES R. HASKELL, of Passaic, in the county of Passaic and State of New Jersey, have invented a new and useful Wad or Gas-Check to be used in Combination with Multicharge or Accelerating Guns; and I do hereby declare the following to be a description thereof in such full, clear, exact, and concise terms as to enable any one skilled in the arts to which it appertains or with which it is most nearly connected to make and use the same, reference being had to the annexed drawings, making a part of this specification, and to the figures and letters of reference marked thereon.

This invention appertains more especially to the multicharge or accelerating gun having supplemental-charge chambers, and is intended to render that variety of gun thoroughly effectual in practice. This gun, although a weapon of very great power when provided with an effectual "gas-check wad," is of no practical value without it. The gun, to be available in actual practice, must be supplied, in loading it, with a gas-check wad that will effectually extinguish "windage"—that is, prevent the gas from passing it and firing the supplemental charge ahead of the shot, and one that will resist the destructive power of the burning powder during its passage through the bore of the gun over the throats of the pockets or supplemental charge-chambers. The throats of these pockets in a ten-inch gun, for example, will be about six inches in diameter, and the powder in them is fired the instant the wad begins to uncover it, so that the wad is subjected to the fire of the powder from the time it begins to uncover the pocket until it has passed entirely clear of it. Unless, therefore, the gas-check wad be made to resist the destructive effects of the burning powder as it moves forward, it will be disabled before it passes the second pocket sufficiently to let the gas pass it and fire the powder ahead of the shot. The value of the gun is thus made to depend upon a gas-check wad possessing at least the essential qualities pointed out.

The object of my invention is to provide a gas-check wad for these guns possessing the

features aforesaid; and it consists of a gas-check wad composed of layers of leather cut to the exact size and shape of the bore of the gun, to fit exactly the grooves and bands of the rifling. This wad is built up of successive layers of leather to a length of about twice the diameter of the throats of the pockets, the several thicknesses of leather being tacked together, as in laying up the heel of a boot, or held together by a bolt. In laying up the wad there is interposed between every third or fourth thickness of leather a disk composed of sheet-copper having a flange equal in depth to the thickness of the leather embraced by it, so that the flanges of these disks cover the entire external surface of the wad, so far as they are interposed in building it up, and they may, of course, be continued through the entire length of the wad; but it is not necessary to continue them beyond two-thirds of its length. The flanges of these metal disks are swaged up to the exact size and form of the bore of the gun and its rifling, and the bottom disk is filled with soft metal to embrace the front end of the cartridge. The arrangement and construction are fully shown by the drawings, in which—

Figure 1 is a longitudinal vertical section through the rear part of a multicharge-gun, showing the gun without the breech cap or pin and only one of the supplemental-charge chambers, only so much of the gun being shown as is necessary to show the relation of the gas-check wad to the cartridge and the supplemental-charge chambers. Fig. 2 is a transverse section through the gun and wad.

This wad, as a whole, is shown in the drawings by A, the several thicknesses of the leather by b b, and the metal disks by c c.

By this construction and composition of the wad its exterior surface is protected by an armor of metal composed of the flanges of the several disks, which flanges, by the slight compressibility of the leather or other material, are driven together and into each other by the force of the powder and expanded tightly into the bore of the gun, thus saving the wad from burning and extinguishing all windage, and preventing the flame from "cutting by" the

wad as it passes the throats of the successive pockets to fire the powder ahead of the shot, or when covered by the wad or shot.

To make this "gas-check wad" thoroughly effectual, the bore of the gun, from the breech to the front end of the wad, should be made a little larger—say one-eighth of an inch—than the remaining part of the bore forward, to insure absolute contact of the flanges of the wad 10 with the surface of the bore. Upon the front end of the wad there is combined a layer of lubricating compound, *l*, between it and the shot, to facilitate the passage of the wad and to save the surface of the bore from undue 15 abrasion.

In making these wads it is better to leave about one-third their length uncovered by the flanges of the copper disks, and to cut the upper leather lamina a little larger than the bore of 20 the gun and the copper flanges of the disks, not only to extinguish the windage absolutely, but that they may also thoroughly clean the bore of the gun.

By Figs. 3 and 4 of the drawings is shown 25 a longitudinal and a vertical section of a gas-check wad embracing the essential principles of the one already described—viz., an armor of soft metal covering the rear part of a wad composed of leather or other fibrous material 30 slightly compressible, and grooved to take the rifling or form of the bore under the operation of the impelling force. This wad consists of a cup, *B*, made of soft brass, in length about equal to two-thirds the length of the entire wad, said cup to be filled with laminated leather crowded tightly into it, and in case the wad is longer than the cup, as I prefer to make it, the leather is laid up above and over the top or forward end of the cup, as shown 35 40 by Fig. 5 of the drawings. In the external surface of the cup a series of concentric grooves are cut and filled with a lubricating compound. The surface of the cup is thus made to consist of a series of alternate grooves and ribs, the 45 ribs taking the rifling of the gun in this instance, instead of the flanges, as in the other wad, and the grooves distributing the lubricant over the surface of the wad. The rear end of the cup may be made plain; but I prefer to 50 make it of the form of an inverted cup, to embrace the forward end of the cartridge, as shown by Fig. 1 of the drawings. This form of the wad is intended more especially for large guns, and the walls of the cup should be thick 55 enough to sustain the pressure of the impelling force. The metal cup may, of course, be made the entire length of the wad, or, in other words, the wad may consist of a metal cup filled with leather or some good substitute for leather, 60 and having its external surface grooved and ribbed to reduce as much as possible the resistance of the wad in taking the rifling of the bore. The grooves in the surface of the wad should be made a little deeper than the rifling 65 of the gun, and the ribs should be made quite narrow, to offer as little resistance as possible

in cutting its passage through the grooves and bands of the rifling. This metal wad may be made hollow and the leather or other filling may be dispensed with; but I prefer to make it in the form of a cup, as above described, filled and mounted with leather or other strong fibrous material, because the leather will act quicker, make a tighter wad, and at the same time thoroughly clean the gun. The metal of the wad is made hollow, or in the form of a cup, to lighten it, and more than half of its surface should be cut away in making the grooves between the ribs, the ribs being made narrower than the grooves to reduce the resistance to 80 its minimum.

By Fig. 5 of the drawings is shown a modified form of the wad. In this case the leather is laid up above the cup and the forward end of the wad mounted with a metal head, *B'*, the whole being held together by a central bolt passing through the wad, so arranged that when the wad is compressed by the powder the cup and the head of the wad can slip toward each other on the bolt or central pin that supports or holds the whole together.

By Fig. 6 of the drawings is shown a modified form of the wad, embracing the same principle, substantially, as those above described; but in this case the soft-metal cup *B* is placed 95 in front of the leather wad and embraces the rear end of the shot, fulfilling the double function of extinguishing the windage and rotating the shot. The cup in this case is grooved in its outside surface, the same as in Fig. 3, and for the same purpose, the rear part of the wad being made of laminated leather and embraced by soft-metal disks, as in Fig. 1. The gas-check wad in this case is combined with the shot and makes a part of it; but it fills the 100 same office precisely and has the same substance as a gas-check wad filled and possessed by the other two—viz., a long gas-check wad that effectually extinguishes windage, covered with an armor of metal to save it from destruction in passing the several pockets, and long 105 enough to lap at once well over both sides of the mouth of the pockets, to prevent the flame from cutting around it and firing the supplemental charges before the wad has passed them. 110 This style of wad is more especially adapted to the form of rifling shown in Fig. 7 of the drawings, as the form of wads shown by Figs. 1 and 3 is best adapted to the form of rifling 115 illustrated by Fig. 2 of the drawings.

It is quite common to put a band of soft metal around the rear end of the shot and crease it to make it take the rifling of the gun or to carry a lubricant; but to make the rear end of the shot a gas-check wad long enough 125 to completely close the mouths of the pockets, and having its surface grooved and ribbed for the purpose of reducing its resistance in taking the rifling of the gun, is novel in combination with this variety of gun, to which the 130 invention is limited.

It will be observed that the principal feature

of the invention is an indestructible wad that will effectually extinguish windage, and of such proportion with reference to the throats of the supplemental-charge chambers as to prevent the flame from cutting around it, as above described.

Having thus described my invention, I claim and desire to secure by Letters Patent—

1. A gas-check wad for multicharge guns, consisting of layers of leather or any good substitute for leather, the front part grooved longitudinally to correspond with the rifling of the gun, and the rear part protected by an armor of metal flanged or grooved circumferentially to take the rifling of the gun under the operation of the impelling force, as described.
- 15 2. A gas-check wad consisting of a series of

soft-metal disks or cups interlaid with leather or any good substitute for leather, the leather and disks or cups to be tacked or bolted together to make the wad of the necessary length and unity, as described.

3. A gas-check wad consisting of a soft-metal cup filled or mounted with leather or its equivalent, and having its flange or periphery 25 grooved and ribbed, the cup and leather to be held together by a bolt and metal head, substantially as described.

Dated October 19, 1880.
